(57) **CLAIM**

The ornamental design for a vehicle lower grille, as shown and described.

DESCRIPTION

FIG. 1 is a perspective view of the vehicle lower grille; FIG. 2 is a front view thereof;

FIG. 3 is a top plan view thereof; and,

FIG. 4 is a left side elevation view thereof (where the right side elevation view is omitted since the right side elevation view is mirror image of the left side elevation view). The broken lines shown depict environment only and form no part of the claimed design.
